LATHER MAKING MACHINE

Walter W. Svendsen, St. Paul, Minn., assignor to Morris B. Holmberg, Minneapolis, Minn.

Application July 28, 1954, Serial No. 446,339

3 Claims. (Cl. 299—83)

This invention relates to lather making machines wherein rotary driving of a brush against a confined cake of soap with an attendant supply of water results in the almost instantaneous production of an efficient lather for shaving purposes.

Such devices, principally for use in barber shops, are available at the present time utilizing an electric motor as a source of power, housed in a chamber of a unitary casing which also defines a lather and brush containing chamber, and a third chamber for containing water. Such prior art devices, to my knowledge, have involved a multiplicity of parts, are expensive and somewhat large and cumbersome and are not well adapted to domestic or home use.

It is an object of my present invention to provide a simple and very compact lather making machine having a relatively high efficiency and involving a minimum number of working parts.

Another object is the provision of an improved, small device of the class described wherein renewal of water and soap supplies is most convenient and wherein the production of lather with heat supplied and dispensing of the same is almost instantaneously produced and controlled.

Further objects of my invention are the provisions of a simplified and more efficient water level control, higher efficiency in the fast production and heating of efficient lather through an agitator-type rotary brush; prevention of drying or caking of soap in the lather chamber; and further the urging of the rotary brush with proper pressure against the soap during all stages of consumption or wear of the soap cake.

These and other objects and advantages of my invention will more fully appear from the following description, made in connection with the accompanying drawings wherein like reference characters refer to the same parts throughout the several views and in which:

Fig. 1 is a view mostly in vertical section along the longitudinal center line of an assembled embodiment of my invention, a portion of a side wall of the housing and control member and spout cover being left and shown in full lines and some of the other parts being broken away beyond the general vertical plane of section;

Fig. 2 is a cross section taken on the line 2—2 of Fig. 1 with some portions broken away; and

Fig. 3 is a side elevation of the sealed water container and depending discharge spout with the lower portion of said spout shown in vertical section.

Fig. 4 is a top plan view of the base plate or cap.

Referring now to the embodiment illustrated in the drawings, all of the working parts of my improved mechanism with the exception of a combined control member and spout cover are housed within a very compact and ornate housing comprising a main body 6, a removable, shell-shaped housing cover 7 and a base plate or cap 8. The housing comprising such parts with certain additional closures or covers may all be constructed from suitable materials such as Bakelite, plastic or light

2

metal, dielectrical materials being preferred. The main body 6 of the housing is molded or otherwise formed to constitute an intermediate vertical partition 6a and substantially aligned horizontally extending generally substantially rectangular chambers 6b and 6c, said chambers extending through the ends of the housing body 6 and being suitably covered or closed as will later be explained. The rectangular chamber 6b is greater in length than chamber 6c and constitutes the lather chamber where, through abrasive rotary action of the bristles of a brush rotor indicated as an entirety by the numeral 9, lather soap is progressively removed from a conventional shaving soap cake S and, with a controlled supply of water, is swirled and foamed to almost instantaneously form an efficient lather.

The smaller rectangular chamber 6c houses an inexpensive but efficient electric motor M preferably of the shaded pole-type. The motor case is almost concentrically secured within chamber 6 as by bolts 10, suitable means such as live rubber washers or plugs being interposed between the supporting connections to minimize vibration and noise. The vertical partition 6a of the housing body 6 is provided with a substantially central horizontal bore 6d to accommodate the armature shaft 11 of motor M which projects therethrough axially into the lather chamber 6b and preferably has a flatted outer portion, as shown in Fig. 2, upon which the hub 9a of the brush rotor is affixed with inherent provision for relative longitudinal sliding movement thereon in revolution. Chamber 6c is sealed with respect to the motor shaft-receiving bore 6d through suitable means such as the provision of an O-ring 12 disposed between the shaft 11 and the annular shoulder of a recess formed in partition 6a at the motor chamber side thereof.

The brush rotor 9 is preferably formed throughout the major part of its axial length with a plurality of circumferentially spaced, partially spiral blades 9b which emanate and may be integrally formed with the hub 9a and which are canted to produce propulsion of the rotor or head during revolution of the motor shaft 11 in a direction towards the outer end of the lather chamber where the soap cake or bar S is fixedly positioned. The outermost end of the brush rotor 9, as shown, is formed into an integral disc head 9c which, as shown, has secured in suitable sockets thereof a multiplicity of diverging bristle units 9d. As shown, the positioning of the several bristle units is generally in the arrangement of radially and semi-spiralled vanes extending similarly in curvature to the blades 9b of the rotor body and extending normally for some distance beyond the head disc 9c.

I provide a soap holder cover 13 having a cylindrical sleeve which is externally threaded, as shown in Fig. 2, to threadedly engage a large internal thread at the left-hand end of the housing body 6, said cover 13 having an outer head or disc 13a which is adapted to seal at its overlying shoulder with the adjacent end of the housing body and which, as shown, has its circumference knurled to facilitate application and detachment thereof. The sleeve 13b of the soap holder is internally provided with suitable means for non-rotatively holding a cake or bar of soap and, as shown, a plurality of longitudinal, circumferentially spaced internal ribs 13c are provided in the sleeve protruding only slightly beyond the internal periphery of the sleeve and which will gouge a cake of soap when the same is forcibly applied and held within such sleeve, thereafter preventing relative rotation of the cake to the anchored sleeve.

The housing cover shell 7 is streamlined substantially arcuately at the ends thereof and terminates in a lower rectangularly arranged skirt or edge which frictionally interfits with a rabbeted shoulder 6s formed in the gen-

erally planar top of housing 6. Within shell cover 7, a readily removable sealed water reservoir 14 is housed comprising a shallow base section 14a having an upturned annular flange which is internally threaded to engage the skirt 14c of a relatively high container cover member 14b. The cover member 14b and base section 14a must have a water-sealed relation when united which may be effected through the proper threaded joint between skirt 14c and flange of base section 14a. Base section 14a rigidly carries a depending open discharge tube 15 which, as shown, is slightly eccentrically disposed of the base section extending perpendicularly thereto and having a downwardly tapered extremity 15a which, as shown in Fig. 3, internally forms a valve seat to engage a ball check valve 16 which is spring-pressed downwardly by spring 17 against the seat so formed. The discharge tube 15 of my water reservoir is closely accommodated in a vertical bore 6e formed through vertical partition 6a. A lateral discharge opening 6f (see Fig. 1) is formed in the lather chamber side of partition 6a, thereby communicating the lower portion of bore 6e between the lower extremity of the dispensing tube 15 with the bottom of the lather chamber. The bottom portion of partition 6a within the bore 6e carries a vertical upstanding valve-operating pin 18 axially aligned with discharge tube 15 when the reservoir is inserted properly and supported upon the planar top of housing body 6.

It will be understood that the reservoir 14 is freely mounted upon housing body 6 with the discharge tube 15 loosely accommodated in the partition bore 6e and is readily removable for re-filling from the housing when the shell cover 7 is first removed. When removed, the shell base portion 14a with the tube 15 is threadedly detached from cover 14. Cover 14 is then filled with water in the inverted position and the base section 14a is then threadedly and tightly attached to the cover portion forming a sealed joint therewith. Thereafter the reservoir 14 may be reversed to its normal position, the ball check valve 16 being closed by the weight of the liquid contained and spring pressure.

Produced lather is discharged during operation from the upper and medial portion of lather chamber 6b through a tubular discharge spout 19 which is tightly fitted into a circular aperture appropriately formed in one of the side walls of the housing body 6, as shown in Fig. 2. A combined control lever and spout cover 5 is pivotally connected with the upper portion of housing 6 through a rigidly affixed horizontal, small control shaft 20 which is received in a small transverse bore drilled into the top wall of the housing body 6, as shown in Fig. 2. The control lever, as shown, is of generally oval configuration having its upper and diminished end affixed to shaft 20 and having a flat back portion 5a which normally extends flush against the exterior face of spout 19, covering the same in normal inoperative position. The control member 5 includes a curved downwardly concave projecting lip 5b for conveniently receiving the thumb or one finger of a hand to facilitate controlled operation of the machine and simultaneous opening of the spout 19 through upward shifting of the member 5.

Within the confines of the shell housing top 7 in a compartment 7a defined at its inner end by a vertical partition 7b is mounted a swingable mercury tube switch 21 carried, as shown, by a saddle 21a which is attached in angular relation to an upstanding supporting arm 20a affixed to the inner end of the small control shaft 20. A suitable recess 6g is formed in the appropriate upper portion of the top plate of housing body 6 communicating with shaft 20 to accommodate swinging movement of supporting arm 20a when control lever 5 is shifted. A leaf spring 22 is affixed at its outer end to the top of housing body 6 and has its free end yieldingly applied against the switch mounting arm 20a to normally retain the arm in the inoperative position shown in Fig. 1 with the mercury

tube tilted downwardly from circuit-closing position, said spring 22 serving also to urge control lever 5 to its normal position, as shown in Fig. 1, where the back or body 5a thereof closes the discharge of the lather spout 19.

- 5 The base plate or cap 8 previously referred to as comprising a part of the machine housing is of generally rectangular form having certain channels formed in the upper portion thereof and provided with a marginal retaining flange or edge 8a which extends rectangularly around the entire margin of the cap proper and is received in a correspondingly recessed or rabbeted portion of the bottom of housing body 6 along the generally rectangular edge of such body at the bottom of the lather chamber 6b. This base plate 8, at its upper portion is provided, as 10 shown in Fig. 4, with a transverse, rectangular recess 23 adapted to accommodate a suitable electrical heating element designated as an entirety by the numeral 24 and also forming a sump for receiving a small quantity of water to be converted into steam. Communicating with 15 recess 23 is a narrow channel 6f which extends inwardly to a position below the discharge end of the water tube 15. Base plate 8 at such portion is provided with a rectangular extension to provide a bottom to the socket or bore 6e in which the reservoir discharge tube is housed and the 20 valve-operating pin 18 is imbedded and supported from the channel portion of this extension axially aligned with tube 15. Any suitable electrical heating element of immersion type may be used such as, merely for example, the structure illustrated in the expired Hanks Patent No. 30, 1,881,531.

The said electrical heating element, the motor M and mercury tube switch 21 are all connected in series forming an electrical circuit, service wires for said circuit being electrically connected to an electrical plug-in socket 25 35 which may be conveniently mounted in one of the side walls of the device being preferably partially countersunk.

Opération

- 40 In use with the reservoir 14 filled with water and a cake of soap S retained in the soap-holder cover 13 and in contact with the ends of the bristles 9d, the motor M and heating element 24 are energized by closing the circuit through the upward shifting of the combined control lever and spout cover 5. The swinging of member 45 5 through rocking of the small control shaft 20 effects tilting of the mercury tube switch 21 to close the circuit. The control member 5 is conveniently swung upwardly with a thumb or forefinger and simultaneously the spout 19 is opened and the user continues for a few seconds 50 to hold the member 5 in upward position whereafter shortly lather is made and ejected through spout 19 onto the other fingers of the user which naturally are disposed below such spout.

The water level at the bottom of the housing substantially at the top surface of bottom plate 8 will be maintained constant, filling the channel 23 through the barometric-seal principle of reservoir 14 and its valve-equipped discharge tube 15. In other words, discharge water rises until it seals the lower end of discharge tube 15, the 60 vacuum produced in the top of the operatively positioned reservoir above the head of water therein preventing further flow of water from the discharge tube. It is to be remembered that, upon insertion of the discharge tube 15 fully into its receiving bore 6e, the pin 18 opens the ball valve 16.

Not only is lather formed by the revolution of the ends of bristles 9d against the inner face of the soap bar S, but the radially disposed blades 9b of the rotor head rapidly agitate lather and water within the entire lather chamber, thereby constituting an effective contributing factor in the almost-instantaneous production of lather. Because the brush rotor with its bristles occupies the greater part of the space within lather chamber 6b, and because of the spiral blades 9b constituting an agitator, lather formed with a minimum and controlled supply of

water and mixture of soap and water is conveyed rearwardly past the bristles and circumferentially of the brush rotor, accumulating or backing up against the partition 6a of the housing and thereafter flowing upwardly and forwardly to the discharge spout 19. This insures a formation of an excellent lather before discharge thereof which is adequately heated by the rising steam or hot vapor from the sump 23 in the base plate. In operation, it takes only a few seconds upon forward displacement of the control member 5 for discharge of heated lather onto the fingertips of the user through spout 19.

Immediately upon release of the control member 5, switch 21 is returned by the leaf spring 22 to open the circuit and stop operation of the motor and heating element. Simultaneously the discharge opening of spout 19 is closed and substantially sealed by interposition of the body 5a of the control member. With my structural combination and the electrical circuit utilized therein, there can be no drying of soap in the lather casing from heating or danger of accident through continuance of the heating operation after the control member is released, because the circuit to the heating element is immediately opened when the fingertip control member 5 is released.

In the revolution of the brush rotor, the partial spiral contour of the radial blades 9b and also, to some extent, the spiral arrangements of the series of bristle units 9d, propel the rotor and brush in the direction of the exposed face of the soap cake S. The brush rotor 9 is free to slide, as has been previously stated, on the flatted shaft 11 so that the proper degree of friction of bristle tips upon the soap is always maintained during successive wear upon the cake of soap S.

The high efficiency of the revolving lather-producing means including the rapid agitation effected by the agitator blades 9b and the compact relationship of motor M and the removable water reservoir enables my device to require only minimum volumetric space for mounting and housing of all of the cooperating parts. The simplicity of the device and minimum number of parts required enables my device to be manufactured at relatively low cost to the end that it is well adapted for sale to individual users.

It will, of course, be understood that various changes may be made in the form, details, arrangement and proportion of the parts without departing from the scope of my invention.

What I claim is:

1. A lather mixing machine having in combination a housing defining a lather chamber, a medial partition and an adjacent motor-receiving chamber, a vertical socket in said partition extending to and in communication with the bottom of said lather chamber for receiving the discharge tube of a removable water reservoir, a water reservoir removably mounted on said housing with its discharge tube depending in said socket and having means associated therewith for controllably supplying water to said lather chamber, means for holding a bar of soap within the outer end of said chamber, a brush head

mounted in said lather chamber and occupying most of the space therein and disposed substantially coaxially with the bar of soap and carrying a multiplicity of bristles at its outer end for contact with said soap, said brush head having radially extending agitating and propelling blades extending from the periphery thereof and a driving shaft having sealed relation through said partition and connecting said motor with said brush head.

2. A lather mixing machine having a mounting defining a lather chamber, means for holding a bar of soap within said chamber, a motor supported on said mounting externally and at one end of said lather chamber, a brush head mounted in said lather chamber, driven by said motor and disposed within said chamber and carrying bristles contacting said soap, a water reservoir supported from said mounting and controllably supplying a small amount of water to the bottom of said lather chamber, an electrical heating element of immersion-type disposed in the bottom of said lather chamber for rapidly heating the small amount of water discharged, a control member having a handle mounted exteriorly of said mounting and adapted to be shifted to open a discharge spout for lather as well as to actuate an electrical switch, and an electrical circuit including said switch with means for normally holding said switch open and including said motor and said electrical heating element, all connected in series whereby when said control member is released said switch will be opened and said electrical heating element in said motor will simultaneously be deenergized.
3. In a lather mixing machine, a mounting defining a lather chamber, means for holding a bar of soap substantially vertically disposed at one end of said chamber, a horizontal driven shaft mounted in said chamber with its axis substantially aligned with the central portion of said soap bar, a brush head mounted upon said shaft in said chamber and having non-rotatable but longitudinally slideable connection with said shaft and carrying a multiplicity of bristles at its outer end for contact with said soap, said brush head inwardly of said bristles carrying a plurality of circumferentially spaced elements spiraled relatively to the directional revolution of said shaft to propel said head upon said shaft in the direction of said soap to apply the proper degree of friction between the ends of said bristles and said soap during successive wear of said soap and means for controllably supplying water to said chamber.
